DESIGN FOR A DOLL

Erland L. Curtis, Ferndale, Mich.

Application November 25, 1946, Serial No. 135,068

Term of patent 7 years

(Cl. D34—4)

To all whom it may concern:

Be it known that I, Erland L. Curtis, a citizen of the United States, residing at Ferndale, county of Oakland, and State of Michigan, have invented a new, original, and ornamental Design for a Doll, of which the following is a specification, reference being had to the accompanying drawing, forming part thereof. In the drawing:

I claim:

The ornamental design for a doll, as shown.

ERLAND L. CURTIS.
